UNITED STATES PATENT OFFICE.

HERMAN SCHLAICH, OF LONG ISLAND CITY, NEW YORK.

INDICATING DEVICE.

Application filed May 10, 1916, Serial No. 478,430. Renewed June 17, 1921.

My invention has reference to devices for indicating an abnormal condition of the cooling liquid of an internal combustion engine; and particularly a device of the kind mentioned which is adapted to be responsive to pressure in the circulatory system containing the liquid in case the cooling liquid becomes heated to the point of vaporization, in order to give warning of the state of affairs 10 to an attendant.

The object of my invention is to provide such an indicating device which is designed primarily for use in connection with the engines of automobiles and motor vehicles in 15 general; and which is preferably so constructed that it can easily and quickly be mounted on the radiator by which the cooling liquid is treated to lower the temperature of the same, after passing through the jacket enclosing the power cylinders of the engine.

The above and other objects and advantages of my invention are set forth in the following description taken in connection with the accompanying drawings, which illustrate 25 one or more forms in which the principle of my invention can be embodied. This specification, however, is to be construed as illustrative only; and embodiments of my invention other than those actually shown herein 30 may be adopted, to the extent defined by the meanings of the terms in which the claims appended hereto are expressed.

On the drawings,

Figure 1 is a view showing an engine and 35 a radiator for the cooling liquid, with an indicating device made according to my invention applied thereto.

Figure 2 is a vertical sectional view of an indicating device made according to my invention;

Figure 3 is a view of the same indicating device, with the parts in different positions; and

Figure 4 is a vertical sectional view of another indicating device made in accordance with my invention; and

Figure 5 is a side elevation, partly in section, of a structure embodying a modified form of the invention.

50 The same numerals of reference identify the same parts throughout.

In Figure 1 I show at 1 an internal combustion engine having a jacket 2, to which a suitable cooling liquid, such as water, is supplied 55 by a pipe 3. This pipe leads from a radiator 4, and the water is returned from the en-

gine to the radiator by a pipe 5. The jacket, the radiator and the pipes constitute means for circulating the cooling liquid through the engine; and, if desired, the circulation may be maintained by interposing a pump, not shown, in the line of the pipe 3. As will be understood, the engine 1 may be mounted at the forward end of a motor vehicle, with the radiator in front of it in the usual way; and as the air comes into contact with the radiator on the vehicle when the latter moves along, the water passing from the engine 1 to the radiator will have its temperature lowered, and the liquid in the circulating means is thus prevented from getting overheated under ordinary practical conditions. My device for indicating an abnormal condition of the cooling liquid is shown at 6 in Figure 1; and I prefer to mount the same at the top of the radiator; so that if the water should ever, under any circumstances become heated to the boiling point, the pressure of the steam in the radiator above the level of the liquid therein will actuate the indicating device, and make the fact known to the driver.

On the top of the radiator at the front end thereof is an opening 7 for admitting water to fill the radiator and maintain the desired quantity of the cooling liquid; and this opening can be sealed by a cap or closure 8. The top portion of the radiator is formed so that it encloses a space above the level of the liquid and below the cap 8; and this space is prevented from being occupied by the liquid by an opening 9, a little above the mouth of the pipe 5, and constituting an inlet to a tube 10. This tube 10 leads down under the vehicle and prevents overfilling of the radiator; and if the water is ever caused to vaporize, the steam formed in the space above the liquid will be vented through the opening 9 and tube 10 at a rate sufficient to obviate danger of the radiator being burst open.

The indicating device 6 may be constructed in various ways, but the one shown in Figures 2 and 3 comprises a hollow casing 11, preferably round, and formed of upper and lower sections 12 and 13; joined together so as to be enabled to receive between them a pressure-responsive element in the shape of a corrugated diaphragm 14. I provide a threaded hole in the cap 8, and the lower section 13 has a hollow threaded boss to be screwed in the hole in the cap; and as the boss has a bore therethrough, the casing 11 is in communication through the cap with

the space inside the radiator above the opening 9. The rim of the lower section 13 may be inturned to enable the diaphragm to rest thereon; and the rim of the upper section 12 5 may be bent outward and downward; making an inverted shoulder against which the edge of the diaphragm fits. Of course the sections and the diaphragm may be soldered together, and the diaphragm may be flat in- 10 stead of corrugated if preferred.

The upper section 12 supports a part controlled by the diaphragm and comprising a vane 15 on a rotatable stem 16, the vane being outside the casing, and the stem extending 15 through a central bearing in the upper section into the casing 11. On the inner end of the stem 16 is secured a laterally extending pin 17; which normally contacts with a pawl or arm 18 on a stud 19, secured to the 20 diaphragm 14. When pressure in the circulating means raises the diaphragm, the pin 17 and arm 18 are moved out of engagement, so as to enable a coiled spring 20, fixed at one 25 end to the stem 16 inside the casing, and anchored to the casing at the other, to rotate the stem 16 and move the vane.

In practice, so long as the temperature of the cooling liquid is kept by the radiator below the boiling point, no warning is needed 30 by the chauffeur, and the indicating device 6 is not actuated. The vane 15 therefore remains stationary; extending either outward to one side, or directly towards the driver's seat. When the water gets heated to the point 35 at which vaporization takes place, the pressure in the radiator above the water greatly increases at once, even though some of the vapor is discharged through the tube 10; and the diaphragm is forced upward. This action liberates the pin 17, and the spring 20 throws the vane over to present a particular side to the driver and notify him that trouble 40 has developed. The side in question will be given a conspicuous color, so as to attract attention; and when the driver sees it, he acts accordingly. After taking the needed measures to prevent injury to the engine, the chauffeur turns back the vane by hand. To 45 permit the return of the vane in this way, the arm 18 may be made to rest upon a collar 21, fixed to the stud 19, and having a projection 22 at its upper edge to engage the arm 18. A spring 23 will keep the arm 18 against the projection 22, but will allow the arm or 50 pawl 18 to yield, and the pin 17 to pass it on the return of the pin. When past the pawl 18, the pin 17 will be prevented from being moved by the projection 22, till the diaphragm rises and moves the pawl 18 above 55 the pin 17.

Before actuation of the diaphragm, the parts are as indicated in Figure 2; after vaporization in the radiator the parts appear as in Figure 3.

60 65 A stop 24 may be employed to limit the

movement of the vane by the spring 20; and this stop 24 may be made integral with the stud 19; giving the latter the shape of a yoke; or it may be made separate and secured to either the diaphragm or the casing, as will be understood. The vane constitutes spring-actuated means, releasable by the diaphragm, to produce the wished-for result.

The indicating device 12-24 of Figures 2 and 3 can also be mounted on the dashboard, in which case a tube 13^a may connect the boss of section 13 to the cap 8. Disclosure is made of such an installation in Figure 5. The parts in Figure 5 are generally similar in structure and function to the parts shown in Figures 1 to 3, and corresponding reference numerals have accordingly been applied in Figure 5.

In the indicating device illustrated in Figure 4, the rim of the section 13 is turned out and up to provide a shoulder on which the edge of the section 12 may rest; and two diaphragms 14, both located in the lower section 13, are used. These diaphragms are joined together along their peripheral edges, 90 constituting a hollow expansion body, whose interior communicates with the inside of the radiator above the water level through a short tube 25. This tube is made rigid with the lower diaphragm 14 in any suitable way; as by screwing one end into a threaded opening in a boss fixed to the middle of the lower diaphragm; and it may be secured to the casing by screwing the other end to a fixed disk placed inside the boss on the section 13, and having a threaded hole at the center for this purpose. Hence the tube 25 not only allows the steam to get between the diaphragms 14 and distend them; but it also serves to support them in the casing. As in the two preceding views, there is a rotatable part or element controlled by the diaphragms, and including a vane 15 and a stem 16. The upper diaphragm has a hollow stud 26 with a spiral groove or slot 27; and the pin 17 on the stem 16 is engaged by this slot. Hence when the upper diaphragm is elevated by pressure in the radiator, the stem is rotated and the vane turned. When this pressure no longer affects the diaphragms 14, so that the upper diaphragm falls, the vane is returned automatically to its original position. In this modification of my indicating device, the vane is protected by a glass top 28, resting on the edge of the section 12, within the rim of the section 13.

From the above description, it will be seen that my indicating device in all its forms is simple in design and sure in operation. Whenever steam is formed in the water jackets of the engine, it must find its way into the radiator and be vented by the tube 10; hence the device cannot fail to work and give evidence of the fact to the chauffeur when the latter should know what is going on.

Having described my invention, what I believe to be new and desire to secure and protect by Letters Patent of the United States is:—

5. 1. The combination of an element providing a convex surface on one side, a vane mounted to rotate adjacent said surface, means on the opposite side of said element for rotating the vane, and a dome-shaped transparent cover for said vane having its periphery secured adjacent the border of said convex surface.
10. 2. In an exposed indicating instrument readable at a distance, the combination of a casing containing operating mechanism, an upstanding flag-shaped indicating member operated thereby, and a dome-shaped transparent, protecting cover enclosing said indicating member, the upper edge of said indicating member being shaped to follow substantially the curvature of said dome.
15. 3. In an indicating instrument, the combination of a casing containing operative mechanism, a convex plate enclosing said mechanism within the casing, a rotatable member projecting through the center of said plate and actuated by said mechanism, a vane carried by said member, the edge of said vane adjacent said plate being curved so that it moves in a path equidistant from said plate, and a transparent cover enclosing said vane and conforming in contour to the path of the other edge of said vane.
20. 4. In a motor vehicle, the combination with a motor, of a system for circulating a cooling liquid to control the temperature of the motor, said system being sealed against flowing of liquid or vapor from the top thereof and having an air space above the level of the cooling liquid, an open vent communicating with said space and normally maintaining the system at atmospheric pressure, a visual danger indicator in view of the operator, and pressure actuated means constructed and arranged to set the indicator to a warning position when super-atmospheric pressure occurs in the system.
25. 5. In a motor vehicle the combination with an internal combustion, vehicle propelling motor, of a cooling system for said motor comprising a radiator, a filling neck therefor, an overflow pipe leading from the radiator to maintain a space in the radiator above the cooling liquid, in which steam may accumulate when the cooling liquid boils, a cap for sealing the filling opening of the radiator to prevent the escape of steam through said opening, and a pressure responsive visual warning instrument mounted on said cap.
30. 6. In a motor vehicle the combination with an internal combustion, vehicle propelling motor, of a cooling system therefor, comprising a radiator, a conduit communicating with the radiator below the top there-
- of for carrying off the liquid above the conduit and thereby limiting the level to which the liquid may rise in the radiator so that an air space is provided in the upper part 65 of the radiator, said conduit also maintaining the air space in communication with the atmosphere and normally at atmospheric pressure but constructed to limit the rate of escape of air and steam from the radiator when boiling of the cooling liquid occurs so that the pressure in the air space may be 70 raised by the generation of vapor, said radiator having a filling opening in the top thereof, a cap for sealing said opening, a visual indicator carried by said cap in view of the operator of the vehicle, and pressure responsive means also carried by the cap and exposed to the pressure in the air space for causing pressure occurring within the air space 75 of the radiator to operate the indicator to warn of danger.
35. 7. The combination of means for circulating the cooling liquid of an internal combustion engine, a closure for said means, a casing carried by the closure and having an outside convex surface at its top, a vane mounted to move adjacent said surface, means in said casing responsive to pressure for controlling the actuation of said vane, and a dome-shaped transparent cover for the vane having its periphery secured to the casing 80 around the border of said surface.
40. 8. A device of the class described including a spout closing member, an indicator hinged thereto, a spring for shifting said indicator from a normal position, means normally retaining said indicator in said normal position, a diaphragm mounted on said spout closing member, and a member operated by said diaphragm arranged to render said retaining means ineffective at a predetermined 85 change in pressure within the spout.
45. 9. A device of the class described comprising a body provided with an indicator movably mounted on said body, a spring for instantly shifting said indicator from non-indicating position to full indicating position, means for retaining said spring against operation, and pressure operated means for releasing said spring.
50. 10. A device of the class described comprising a body provided with an indicator movably mounted on said body, means for instantly shifting said indicator from non-indicating position to full indicating position, a latch for normally retaining said indicator in non-indicating position, and fluid pressure operated means for rendering said retaining 90 latch ineffective.
55. 11. In a motor vehicle, the combination with a motor, of a system for circulating a cooling liquid to control the temperature of the motor, said system being sealed against flowing of liquid or vapor from the top there-
95. 12. 13. 14. 15. 16. 17. 18. 19. 20. 21. 22. 23. 24. 25. 26. 27. 28. 29. 30. 31. 32. 33. 34. 35. 36. 37. 38. 39. 40. 41. 42. 43. 44. 45. 46. 47. 48. 49. 50. 51. 52. 53. 54. 55. 56. 57. 58. 59. 60. 61. 62. 63. 64. 65. 66. 67. 68. 69. 70. 71. 72. 73. 74. 75. 76. 77. 78. 79. 80. 81. 82. 83. 84. 85. 86. 87. 88. 89. 90. 91. 92. 93. 94. 95. 96. 97. 98. 99. 100. 101. 102. 103. 104. 105. 106. 107. 108. 109. 110. 111. 112. 113. 114. 115. 116. 117. 118. 119. 120. 121. 122. 123. 124. 125.

of and having an air space above the level of the cooling liquid, an open vent communicating with said space and normally maintaining the system at atmospheric pressure, a visual danger indicator in view of the operator, and pressure actuated means constructed and arranged to operate the indicator to warn

of danger when super-atmospheric pressure occurs in the system.

In testimony whereof, I have signed my name to this specification, this 24th day of April 1916.

HERMAN SCHLAICH.
